UNITED STATES PATENT OFFICE.

SILAS TAPPIN, OF WEBSTER, SOUTH DAKOTA.

GRAIN-DOOR FOR BOX-CARS.

967,856.

Specification of Letters Patent. Patented Aug. 16, 1910.

Application filed November 3, 1909. Serial No. 526,134.

To all whom it may concern:

Be it known that I, SILAS TAPPIN, a citizen of the United States, residing at Webster, in the county of Day and State of South Dakota, have invented new and useful Improvements in Grain-Doors for Box-Cars, of which the following is a specification.

This invention relates to an improvement in doors for grain cars, being specifically directed to a door adapted for travel in a track way and made up of a series of connected sections, the door construction being positively operated in both directions and locked in any desired position at the pleasure of the operator.

The main object of the present invention is the provision of a grain car in which are arranged track ways to slidably receive the ends of the door sections, the tracks being arranged so that the respective doors may when fully opened be housed in the upper portion of the car, each door being connected with an operating shaft through the medium of a cable connection so that either door may be positively moved in either direction at the will of the operator.

The invention in the preferred form of details will be described in the following specification reference being had particularly to the accompanying drawings, in which,

Figure 1 is a view in side elevation partly in section and illustrating the improvement. Fig. 2 is a section on the line 2—2 of Fig. 1. Fig. 3 is a vertical section through the car structure showing both doors in closed position. Fig. 4 is a perspective detail showing the connected sections of the door. Fig. 5 is an enlarged view illustrating means whereby the door may be locked at any desired position.

Referring particularly to the accompanying drawings wherein is illustrated the preferred details of construction it will be noted that the doors 1 and 2 designed to close the usual door openings in the car are of identical construction and hence a detail description of only one suffices for both.

Each door is made up of a series of connected duplicate sections 3 preferably of a length slightly greater than the width of the door opening, and of comparatively narrow width. The sections have their meeting edges matched, as at 4 so that a grain tight connection is maintained between the

sections. The sections are movably connected through the medium of hinged strips 5 which extend the full width of each section on the inner side and serve to strengthen as well as hingedly connect the sections. Any desired number of hinged connections may be used, three being illustrated, as shown in dotted lines in Fig. 1. Each section 3 of the door is provided adjacent each end with what I term a guide plate 6 having a relatively outer edge turned laterally or at right angles to the surface of the section to provide a lip 7. The uprights 8 at the sides of the door opening are cut away or recessed throughout their lengths on their inner and side edges to form recesses 9 of rectangular outline in section and in which are secured wear plates 10 conforming in shape to the walls of the recess. The sections 3 are of a length less than the distance between the walls of opposing recesses, so that when the forward faces of the sections bear against the forward portions of the wear plates 10, there is a space between the ends of the sections and the side portions of the wear plates. A tie plate 11 underlies the lower edge of the lowermost section, said plate being of a length corresponding to the distance between the side portions of the wear plates and projecting at each end beyond the approximate edge of the lower section of the door. The tie plate thus forms a guide for the movement of the door and the projecting portion thereof is formed with an opening to receive eye bolts 12 and 13 for a purpose which will presently appear.

With the door sections in place in the recess 9 it will be understood that the lips 7 of the guide plates extend in parallel relation to the side portions of the wear plates 10. A sealing plate 14 is secured to the inner surface of each upright 8, that edge of said plate adjacent the door being formed with an outwardly turned lip 15 to overlie and bear against the lip 7 on the wear plates. By this means the door is secured in the recess and the juncture between the door and upright is sealed to prevent the escape of grain at this point.

On the inner side of each upright is secured a tube 16 which extends throughout the length of the upright and through the floor of the car opening through the bottom thereof as shown in Fig. 1. A tubular opening 17 is also formed in the floor of the car in alignment with the recess 9. Below each door

opening in parallel relation to the door is arranged a shaft 18 carrying drums 19 and 20 on each end, the shafts being supported in brackets 21 depending from the bottom of the car. An elevating cable 22 is wound about one drum as 20 and passed through the tube 16, over a pulley 23 mounted in the upper portion of the car and from said pulley down the recess 9 to the upper eye bolt 10. A second cable 24 is wound about the drum 19 in opposition to the winding of the cable 22 on the drum 20 and passing through the opening 17 and secured to the lower eye bolt 13. Adjacent one end of the shaft 18 there is mounted an auxiliary shaft 25 carrying a bevel gear 26 designed to mesh with bevel gear 27 secured on the shaft 18, the shaft 25 having an operating or handle wheel 28 the stem 29 of which is preferably connected with the shaft 25 by pivot connection so that the wheel may drop below the shaft when not in use to avoid unnecessary obstruction. The end of the shaft adjacent the connection with the handle stem is provided with oppositely arranged ratchets 30 and 31 and opposing pawls 32, 33 mounted on the car structure to engage the respective ratchets whereby the shaft may be locked against the movement in either direction at pleasure.

The upper end of the recess 9 or more exactly the wear plate 10 therein communicates with a track way 34 secured to the upper portion of the car structure or the like, the track way 34 being preferably constructed of a single strip of material of U-form in cross section and secured to its side so that the open portion is toward the edge of the door. The track way 34 is of a length to permit the full length of the door to be supported therein, and at the end adjacent the particular door opening in which it operates is curved in coincidence with the recess 9 so as to provide with said recess a continuous track way. The track way 34 for one door is arranged above the track way 34 for the other so that both doors if desired can be simultaneously elevated without interference.

In use, by operation of either shaft 18 in an obvious manner the door may be elevated or lowered in accordance with the direction of movement of such shaft, the door operating freely without binding and without permitting an opening for the escape of grain other than that afforded beneath the door in

the elevation thereof. The sill 35 of the car is preferably provided with a plate 36 containing a recess 37 to snugly receive the tie plate 11 whereby when the door is closed a proper sealing effect is gained.

The various parts are to be constructed of appropriate material and in such sizes as will best adapt them for the purpose for which they are designed. As for example, the sections 3 of the door may be constructed of wood or metal and the cables 22 and 24 made up of a single length of material, rather than two lengths as shown.

Having thus described the invention what I claim as new is:

1. A car door made up of a series of hinged sections, a guide plate fixed to each section and having a portion bent at right angles to the section and projected in alignment with the side edge of the section to provide a lip, bar uprights formed with recesses to receive the door sections, and a sealing plate secured to the surface of the upright to overlie the recess, said sealing plate being formed on its free edge with a laterally projected lip to overlie and engage the lips on the sections, whereby the sealing plate secures the sections against independent hinged movement to serve to guide the door as an entirety in its vertical movement with relation to the sealing plates.

2. A car door made up of a series of hinged sections, a guide plate fixed to each section and having a portion bent at right angles to the section and projected in alignment with the side edge of the section to provide a lip, bar uprights formed with recesses to receive the door sections, and a sealing plate secured to the surface of the upright to overlie the recess, said sealing plate being formed on its free edge with a laterally projected lip to overlie and engage the lips on the sections, said door sections being of a length less than the distance between the opposing parallel walls of the recesses, whereby to provide a space between each edge of the door and the proximate walls of the recesses, and door operating means movable in said spaces.

In testimony whereof I affix my signature in presence of two witnesses.

SILAS TAPPIN.
